UNITED STATES PATENT OFFICE.

WALTER H. HIMES, OF PITTSBURGH, PENNSYLVANIA, ASSIGNOR TO WESTINGHOUSE ELECTRIC & MANUFACTURING COMPANY, A CORPORATION OF PENNSYLVANIA.

SHORT-CIRCUITING DEVICE.

Application filed August 30, 1923. Serial No. 660,120.

To all whom it may concern:

Be it known that I, WALTER H. HIMES, a citizen of the United States, and a resident of Pittsburgh, in the county of Allegheny and State of Pennsylvania, have invented a new and useful Improvement in Short-Circuiting Devices, of which the following is a specification.

My invention relates to centrifugally actuated short-circuiting devices for dynamo-electric machines and it has particular relation to single-phase motors of the commutator type that are adapted to operate, during the starting period, as repulsion 10 motors and, upon reaching a pre-determined speed, as induction motors.

It has been found that the sliding friction commonly encountered in devices of the prior art is a highly undesirable element of the starting operation. It is furthermore necessary to provide a starting device having an action whereby the closed circuit between the commutator segments is effected, at a predetermined speed of rotation, with a 25 quick and positive action.

One object of my invention is to provide a short-circuiting device in which sliding friction is substantially eliminated.

Another object of my invention is to provide a short-circuiting device having a critical action, whereby the closed circuit is quickly established with a snap action upon the attainment of predetermined speed.

35 A further object of my invention is to provide a short-circuiting device for dynamo-electric machines that is arranged as a self-contained and simple unit, permitting detailed assembly and testing independently of the machine and permitting the units to be easily interchanged or replaced.

With the foregoing and other objects in view, my invention consists in the arrangement and details of construction described 45 and claimed herewith and illustrated in the accompanying drawings wherein—

Figure 1 is a view in vertical section through the upper half of a short-circuiting device embodying my invention, a portion 50 of the associated motor shaft and commutator cylinder being shown.

Fig. 2 is a view in end elevation of the device illustrated in Fig. 1, a part of the outer plate being broken away.

Fig. 3 is a detail view in transverse section on the line III—III of Fig. 1, and Fig. 4 is a similar view showing a modification.

In Fig. 1 is shown a portion of a motor of the class hereinabove described, comprising a rotatable commutator 1 and a co-operating short-circuiting device 2 which is mounted upon the commutator shaft 3. The commutator has a plurality of segments 4 of any standard construction and is provided with a smooth front-end face 5 having an inner portion 6 of insulating material.

The short-circuiting device 2 comprises a hub member 7, two substantially circular 70 guide plates 8 and 9, a plurality of balls 11 of conducting material, such as bronze, mounted between the guide plates, and a substantially annular tension member 12 surrounding the balls and tending to restrain them in a central position.

The guide plate or retainer 8 is secured in position against a flange 13 extending from the hub member adjacent to the end face of the commutator and is provided with 80 a plurality of substantially radially disposed slots 14. The outer guide plate 9 is secured in position against a shoulder 15 of the hub by means of a circular lock spring 16 wedged between the inner portion 17 of 85 the guide plate and projecting portions 18 of a retaining ring member 18a secured to the hub. The inner portion 17 of the outer guide plate 9 has cut-out portions corresponding to the projections 18 of the retaining member 18a, providing a bayonet joint, as shown in Fig. 2, which facilitates the assembly and removal of the outer guide plate. 90

The conducting balls are mounted loosely 95 within the slots 14 and are adapted to move along predetermined paths upon the end face of the commutator and to establish, in their outer position 11a, a closed circuit between a plurality of the commutator bars 6 and the outer extremities of the slots 14 in 100 the guide plate 8. In Fig. 3 is shown the arrangement of a ball 11 within a slot 14. The ball is mounted loosely between lips 21 extending from the guide plate 8 and is forced into engagement with the commutator face 5 by the action of the tension member 12, as will be explained hereinafter. In the modification shown in Fig. 4, I em- 105

ploy, in lieu of the balls 11, a plurality of rollers 11', which may be of substantially pure copper, and which may have conical ends 11'' for restraining the rollers in the slots.

The annular tension member 12 is preferably made of a closely coiled garter spring having a circular cross-section and having a wedge-like engagement between the outer guide plate 9 and the outer portions of the balls 11. The wedge-like action of the spring crowds the balls into their central positions adjacent the inner ends of the slots 14 and in engagement with the commutator end face 5. The outer plate serves as a guide for the tension member 12 and has a central portion 19 disposed parallel to the commutator face 5, and merging, at a predetermined distance from the center, into a substantially conical portion 22 extending away from the commutator.

Upon the starting of the armature, there is a force tending to move the balls outwardly under centrifugal action along the paths determined by the slots 14 in the guide plate 8 the outward movement of the balls being opposed by the restraining force exerted by the garter spring 12. As the motor speed increases, the balls move out to a portion of their track where the garter spring is diverted upon the inclined portion 22 of the outer guide member 9. At this moment, the restraining action of the spring, is substantially reduced and the balls move out quickly, under the action of centrifugal force, to their short-circuiting positions, the final position of one of the balls being indicated by dotted lines 11a in Fig. 1. It should be noted that although the total tension of the spring is increased, the increased angle of application of its pressure on the balls actually results in reduced radial pressure but increased lateral pressure.

When the speed of the machine is reduced, the contractive force of the tension member 12 gradually predominates over the centrifugal force acting upon the balls, causing them to recede and break contact with the bars of the commutator. It will be noted from the drawing that the closed circuit established by the balls in their outer positions depends partially upon the well-defined wedging action of the balls between the inner guide plate or retainer 8 and the commutator bars 4. The guide plate carries the armature currents and effectively shunts the garter spring 12, in order to protect the latter from the destructive effect that might result were it permitted to carry current.

In short-circuiting devices of the prior art, the balls have been wedged between the end face of the commutator and the inclined surface of a spring-pressed guide member, whereby a rolling movement could occur on only one of said surfaces. The very ap-

preciable friction which occurred at the other surface as the balls moved either outwardly or inwardly, not only very materially increased the wear of the parts but also greatly increased the sluggishness and the uncertainty of the movement to and from the short-circuiting position.

In my invention, I have substantially eliminated all friction in a device which is remarkably superior in operation to anything heretofore known. The result just mentioned is obtained by replacing the spring-pressed guide member with a stationary guide or abutment member, and employing a coil spring which operates, in effect, like a flexible idler roller between the balls and the abutment member, yieldably wedging the balls into engagement with the end face of the commutator. The convolutions of the spring which happen to be in contact with the balls at any moment perform the function of idler rollers, and the remaining convolutions perform the function of resilient connecting means therefor. The balls thus roll on the commutator and face, the spring rolls on the outer guide member, and the balls and spring roll against one another, thus rendering the device remarkably free from all frictional difficulties.

My short-circuiting device 2, including the hub 7, the guide members 8 and 9, and the interposed balls 11 and spring 12, may be quickly and cheaply assembled as a separate, self-contained unit, by methods well adapted for quantity production, the slots 14 being sufficiently narrow to retain the balls 11. The short-circuiting unit may be fixed on the commutator shaft 3 by any desired means, as indicated at 23. The plates or guide members 8 and 9 have adjacent flanges or offset portions 24 and 25 on their respective peripheries so that the spring cannot fly out in case of over-speeding of the motor or even breakage of the spring. The offset portion 24 of the inner guide-member 8 also serves to carry the ends of the slots 14 to points on the peripheries of the balls remote from the commutator, thereby ensuring the necessary wedging action of the balls between the commutator segments and the end walls of the slots, in the short-circuiting position, as indicated by dotted lines in Fig. 1.

The extreme simplicity of my device permits the carrying of complete short-circuiting devices in stock, arranged to act at various critical speeds, in accordance with the need of the motors for which they are intended. A device of my construction also occupies an unusually small space rendering the device especially adapted for use on motors having only a very limited space available.

While I have shown and described but

two embodiments of my invention, I desire that the disclosed embodiments shall be regarded as illustrative only and that the appended claims shall be accorded the broadest 5 construction consistent with prior art.

I claim as my invention:

1. A centrifugal contact-making device comprising a rotating member comprising two members providing spaced abutment 10 surfaces, a plurality of annularly disposed rolling members between said surfaces in rolling contact with one of said surfaces, said rolling members being movable outwardly under the action of centrifugal 15 force, a plurality of contact members adapted to be engaged by said rolling members in the course of their travel, and anti-friction means yieldably engaging said rolling members in rolling engagement therewith 20 and with the other abutment surface for yieldably opposing the centrifugal movement of said rolling members.

2. A centrifugal contact-making device comprising a plurality of annularly disposed rolling members which are movable outwardly under the action of centrifugal force, a cylindrical commutator member having a plurality of peripheral segment members and having an end surface against 30 which said rolling members roll, a coil spring surrounding said rolling members, and an abutment member for said spring.

3. A centrifugal contact-making device comprising a plurality of annularly disposed rolling members which are movable outwardly under the action of centrifugal force, a cylindrical commutator member having a plurality of peripheral segment members and having an end surface against 40 which said rolling members roll, a coil spring surrounding said rolling members, and an abutment member for said spring, said abutment member having a conical surface, the periphery of which is furthest removed from said end surface.

4. A centrifugal contact-making device comprising a plurality of annularly disposed rolling members which are moved outwardly under the action of centrifugal force, a cylindrical commutator member having a plurality of peripheral segment members and having an end surface against 50 which said rolling members roll, a coil spring surrounding said rolling members, and an abutment member for said spring, said abutment member having an inner surface substantially normal to the axis of rotation, merging into an outwardly inclined surface nearer its peripheral edge.

5. A centrifugal contact-making device comprising a plurality of annularly disposed rolling members which are movable outwardly under the action of centrifugal force, a cylindrical commutator member 60 having a plurality of peripheral segment

members and having an end surface against which said rolling members roll, a coil spring surrounding said rolling members, and means for providing an abutment surface for said spring, said surfaces being 70 further apart near their outer edges than their inner edges.

6. A centrifugal contact-making device comprising a plurality of annularly disposed rolling members which are movable outwardly under the action of centrifugal force, a cylindrical commutator member having a plurality of peripheral segment members and having an end surface against 75 which said rolling members roll, a coil spring surrounding said rolling members, and means for providing an abutment surface for said spring, said surfaces being further apart near their outer edges than their inner edges, and the inner portions 85 of said surfaces being more nearly parallel than the outer portions thereof.

7. A centrifugal contact-making device comprising a plurality of annularly disposed spherical members which are movable outwardly under the action of centrifugal force, a commutator cylinder having a plurality of peripherally located segments and having an end surface against which said spherical members roll, a coil spring surrounding 95 said spherical members, and means for providing an abutment surface for said spring.

8. A self-contained speed-responsive attachment comprising a hub, a guide plate secured thereto and having substantially radially disposed slots, an abutment plate secured to said hub in spaced relation to said guide plate, a plurality of annularly disposed roller members disposed in the 100 space between said plates and having their rolling surfaces projecting through said slots, respectively, means for preventing the passage of the entire roller members through said slots, and a coil spring surrounding 105 said roller members and engaging said abutment plate.

9. A self-contained speed-responsive attachment comprising a hub, a guide plate secured thereto and having substantially radially disposed slots, an abutment plate secured to said hub in spaced relation to said guide plate, a plurality of annularly disposed balls disposed in the space between 115 said plates and projecting partially through said slots, respectively, and a coil spring surrounding said balls and engaging said abutment plate.

10. A self-contained speed-responsive attachment comprising a hub, a guide plate secured thereto and having substantially radially disposed slots, an abutment plate secured to said hub in spaced relation to said guide plate, a plurality of annularly disposed roller members disposed in the space 125 130

between said plates and having their rolling surfaces projecting through said slots, respectively, means for preventing the passage of the entire roller members through said slots, and a coil spring surrounding said roller members and engaging said abutment plate, whereby said roller members may move outwardly under the operation of centrifugal force against the reaction of said spring, the outward movements of said roller members being limited by the outer ends of said slots, the outer portion of said guide plate being inclined toward said abutment plate whereby said roller members, in their extreme outer positions, are forced away from said abutment plate by the centrifugal force pressing the roller members against said slot-ends.

11. A self-contained speed-responsive attachment comprising a hub, a guide plate secured thereto and having substantially radially disposed slots, an abutment plate secured to said hub in spaced relation to said guide plate, a plurality of annularly disposed balls disposed in the space between said plates and projecting partially through said slots, respectively, and a coil spring surrounding said balls and engaging said abutment plate, whereby said balls may move outwardly under the operation of centrifugal force against the reaction of said spring, the outward movements of said balls being limited by the outer ends of said slots, the outer portion of said guide plate being inclined toward said abutment plate whereby said balls, in their extreme outer positions, are forced away from said abutment plate by the centrifugal force pressing the balls against said slot-ends.

12. A self-contained speed-responsive attachment comprising a hub, a guide plate secured thereto and having substantially radially disposed slots, an abutment plate secured to said hub in spaced relation to said guide plate, a plurality of annularly disposed roller members disposed in the space between said plates and having their rolling surfaces projecting through said slots, respectively, means for preventing the passage of the entire roller members through said slots, and a coil spring surrounding said roller members and engaging said abutment plate, said abutment plate being bent outwardly whereby said roller members are caused to move into short-circuiting positions with a snap action.

13. A self-contained speed-responsive attachment comprising a hub, a guide plate secured thereto and having substantially radially disposed slots, an abutment plate secured to said hub in spaced relation to said guide plate, a plurality of annularly disposed balls disposed in the space between said plates and projecting partially through said slots, respectively, and a coil

spring surrounding said balls and engaging said abutment plate, said abutment plate being bent outwardly whereby said balls are caused to move into short-circuiting positions with a snap action.

14. A speed-responsive, circuit-closing device comprising a guide plate having a slot, a weight member having a surface extending through said slot, a contact element having a surface by which said weight member is guided as it moves under the action of centrifugal force and means for yieldingly restraining said weight member against outward radial movement, said movement being limited by the outer end of said slot, said slot-end engaging said weight member on the side opposite to said surface, whereby said weight member, in its extreme outer position, is wedged, by centrifugal action, between said contact element and said slot-end.

15. A speed-responsive, circuit-closing device comprising a guide plate having a disposed slot, a roller member having a rolling surface extending partially through said slot, means for preventing the passage of the entire roller member through said slot, a contact element having a surface in contact with said partially extending rolling surface, and means for yieldingly restraining said roller member against outward radial movement under centrifugal action, said slot being closed at its outer end to limit said movement, the outer portion of said guide plate being bent away from said surface, whereby said roller member, in its extreme outer position, is wedged, by centrifugal action, between said contact element and said slot-end.

16. A speed-responsive, circuit-closing device comprising a guide plate having a substantially radially disposed slot, a spherical member having a surface extending partially through said slot, means for preventing the passage of the entire spherical member through said slot, a contact element having a surface in contact with said partially extending surface, and means for yieldingly restraining said spherical member against outward radial movement under centrifugal action, said slot being closed at its outer end to limit said movement, the outer portion of said guide plate being bent away from said surface, whereby said spherical member, in its extreme outer position, is wedged, by centrifugal action, between said contact element and said slot-end.

17. The combination with the commutator cylinder of an electric motor, of a speed-responsive, circuit-closing device comprising a guide plate disposed adjacent to the end of said commutator cylinder and having a plurality of slots, a plurality of annularly disposed weight members movable in said slots under the action of centrifugal force and

- means for yieldingly restraining said weight members against centrifugal movement, said slots having closed ends for limiting said centrifugal movement and for so engaging 5 said weight members as to cause the centrifugal action to wedge the weight members between said commutator cylinder and said slot-ends. 18. The combination with the commutator cylinder of an electric motor, of a speed-responsive, circuit-closing device comprising a 10 guide plate disposed adjacent to the end of said commutator cylinder and having substantially radially disposed slots, a plurality 15 of annularly disposed spherical members movable in said slots under the action of centrifugal force and means for yieldably restraining said spherical members against centrifugal movement, said slots having 20 closed ends for limiting said centrifugal movement and for so engaging said spherical members as to cause the centrifugal action to wedge the spherical members between said commutator cylinder and said slot-ends. 25 19. A close-circuiting device for a rotor of an electric machine comprising a plurality of spherical members adapted to roll outwardly against the end surface of said rotor under the influence of centrifugal force and 30 a rolling tension member restraining said spherical members in a central position. 20. A close-circuiting device for a rotor of an electric machine comprising a plurality of annularly disposed spherical members 35 adapted to roll outwardly against the end surface of said rotor under the influence of centrifugal force and a tension member of substantially circular cross-section surrounding said spherical members and opposing 40 said movement. 21. A centrifugal device comprising a plurality of members adapted to move outwardly under the influence of centrifugal force and means including a yielding member surrounding 45 said plurality of members and tending to retain said members in central positions, said means being so arranged that the force exerted by said yielding member upon said plurality of members diminishes 50 during the latter portion of the movement. 22. The combination with a dynamo-electric machine, of a close-circuiting device comprising a plurality of members arranged to move from central positions to outer positions, a yielding encircling member for opposing 55 said movement and means whereby, when said machine attains a predetermined speed, said members initially move slowly and later move quickly to said outer positions. 60 23. The combination with a rotatable commutator member of an electric machine, of a close-circuiting device comprising a plurality of spherical members arranged to move 65 outwardly under centrifugal force, a yield- 70 75 80 85 90 95 100 105 110 115 120 125 130
- spherical members for opposing said movement, and a guide means for said restraining member, said guide means causing the initial outward movement of said spherical members to be opposed by substantially the full action of said restraining member and causing the opposing action subsequently to become less effective whereupon said spherical members move with an increased velocity to close-circuit said commutator member. 24. The combination with a rotatable commutator member of an electric motor, of a plurality of spherical close circuiting members arranged to move outwardly under centrifugal force, a yielding tension member surrounding said spherical members for restraining said movement, a guide member for said spherical members and a guide member for said tension member whereby, upon the acceleration of said motor, said spherical members move outwardly, said guide member causing said spherical members, upon reaching predetermined portions of their paths, to displace said tension member and to close-circuit said commutator with a snap action. 25. A short-circuiting device for the commutator cylinder of a dynamo-electric machine comprising a plurality of spherical contact members, means adapted to retain said members in spaced relation for engagement with the end of the commutator cylinder and to guide the members in substantially radial paths, means for engaging 100 said spherical members and placing the same under stress, and means for causing said spherical members, upon reaching a predetermined angular speed, to shift the point of engagement with said means and to move quickly to their short-circuiting position. 26. In combination with a rotatable commutator member of an electric machine, a plurality of spherical close-circuiting contact members arranged to move outwardly under centrifugal force, an annular tension member of substantially circular cross-section surrounding said spherical contact members and tending to retain said members in central positions, and guide means for causing said spherical members, upon reaching a predetermined speed, to move said tension member at an angle to their paths and thereby diminish the restraining action exerted upon said spherical contact members. 27. A short-circuiting device for a dynamo-electric machine comprising a commutator, having an inner body portion and 125 commutator bars mounted upon its circumference, a ball cage mounted adjacent to said commutator and having two substantially circular members, one of said members facing said commutator and being provided

- with a plurality of substantially radially extending slots, the other member being in spaced relation thereto and provided with a central portion disposed parallel to the 5 inner body portion of said commutator cylinder and merging into an outer portion diverging from said commutator, balls of conducting material mounted loosely in the slots of said cage, said balls being adapted 10 to establish, in their outer positions, closed circuits between said commutator bars and said slotted cage member, and an annular tension member of circular cross-section surrounding said balls and adapted to 15 actuate said balls into central positions through a wedge-like engagement between said balls and the outer member of said cage.
28. A short-circuiting device for a commutator of a dynamo-electric machine, comprising a hub member adapted to be secured in abutment to said commutator, a circular cage mounted upon said hub member consisting of two circular members, one of said 25 members facing the end of the commutator and being provided with a plurality of substantially radially disposed slots, another member in spaced relation thereto and having a central portion disposed parallel to the end of said commutator and merging into an outer portion extending away from said commutator, balls of conducting material mounted loosely within the slots of 30 said cage and adapted to engage the end portion of said commutator and to establish in their outer position, closed circuits between the slotted cage member and the commutator
- bars, and an annular tension member of circular cross-section surrounding said balls within the cage and having wedge-like 40 engagement between the outer portion of said balls and the wall of the outer cage member, said outer cage member being also provided upon its circumference with a flange adapted to limit the outward movement of said tension member.
29. A short-circuiting device for a commutator of a dynamo-electric machine consisting of a demountable cage comprising a substantially cylindrical hub member adapted to be secured upon the shaft in front of said commutator, a ball guide plate secured to a flange extending from said hub member adjacent to said commutator, a second guide member having a central portion disposed parallel to the front of said commutator and the outer portion extending away from said commutator, a bayonet-joint means for securing said second guide member to said hub member in 50 spaced relation to said ball guide, said ball guide having substantially radially disposed slots therein, a ball of conducting material mounted in each of said slots and adapted to move loosely between said guide plates and an annular garter spring surrounding said balls and adapted to retain said balls in central positions and in engagement with the end portion of said commutator.

In testimony whereof, I have hereunto 70 subscribed my name this 13th day of August, 1923.

WALTER H. HIMES.
